UNITED STATES PATENT OFFICE.

JESSE E. WERNER, OF PHILADELPHIA, PENNSYLVANIA.

MACHINE FOR SEPARATING ASBESTOS FROM THE ROCK.

1,027,163.

Specification of Letters Patent. Patented May 21, 1912.

Application filed July 12, 1911. Serial No. 638,076.

To all whom it may concern:

Be it known that I, JESSE E. WERNER, a citizen of the United States, residing at Philadelphia, county of Philadelphia, and 5 State of Pennsylvania, have invented a new and useful Improvement in Machines for Separating Asbestos from the Rock, of which the following is a full, clear, and exact description, reference being had to the 10 accompanying drawings, which form a part of this specification.

In separating asbestos from conglomerate rock by means of the usual crushing or pressing action, a fairly large proportion of the 15 fiber is so intimately associated with the rocks and stones that it is not removed. Such rocks and stones are cast aside as waste product.

The object of my invention is to devise an 20 apparatus capable of treating this waste product so as to successfully and economically remove therefrom the associated asbestos.

An apparatus or machine embodying a 25 preferred form of my invention is shown in the accompanying drawings, in which:

Figure 1 is a vertical sectional view of the machine; Fig. 2 is a cross-section on the line 2—2 of Fig. 1; Fig. 3 is a detail view 30 of one of the brushes.

a is a box or enclosure having preferably a depth slightly less than its height, and a width very much less than its depth. Extending between the end walls of the box is an upper 35 drum *b* and lower drum *c*. The shaft of each drum extends through the end walls of the box and turns in bearings *d*, on the outside of the box, mounted upon horizontal beams *e*, the inner faces of the beams being 40 flush with the inside of the box. Upon the two drum shafts are respectively mounted pulleys *f*, *f* connected by a crossed belt *g*. One of these shafts (say the upper one) is a driving shaft and is rotated at the rate of 45 about 1100 revolutions per minute. The diameters of the two pulleys *f* are so proportioned that the shaft of the lower drum will be rotated somewhat more slowly, say about 980 revolutions per minute.

50 On the upper drum *b* is mounted a series of wire cutters *h*. Each cutter is composed of a multitude of wire knives or bristles *k* the inner ends of which extend through segment-shaped plates *l* fastened to the periphery of the drum. Each knife is preferably 55 about one-eighth of an inch wide and about

one-thirty second of an inch or less in thickness. Those knives extending along the front longitudinal face of a cutter are somewhat longer than the knives extending along the rear longitudinal face of the cutter, while the intermediate knives are of intermediate and graduated length. By the front face of a cutter I mean that face thereof that faces in the direction of rotation of the drum. The knives are mounted so that their flat sides face toward the ends of the drums. The outer end of each knife is beveled so that the front edge thereof is slightly longer than its rear edge. The cutters *i* of the lower drum *c* are constructed similarly to the cutters *h* of the upper drum, the only difference being that the thickness of a lower cutter *i*—that is, the distance between its front and rear faces—is less than the thickness of an upper cutter *h*, and the distance between two adjacent cutters *i* is greater than the distance between two adjacent cutters *h*.

The front wall of the box *a* has an inlet *m* 80 for the reception of the rock to be handled. In the bottom of the box is an outlet *n* for the separated rock, this outlet being adapted to be closed by the sliding gate *v*. In the rear wall of the box, near its top, is an outlet *o* for the separated asbestos fiber.

Within the box *a* is a casing composed of an approximately semi-circular hood or dome *p*; an inclined front plate or deflector *r* extending from the lower end of the front of the hood downward and inward, nearly tangentially to the periphery of the lower cutters *i* and terminating close to the said periphery; and an inclined rear wall *s* extending from the lower end of the rear of the hood downward and inward to the outlet *n*.

t is a chute extending from above the outlet *n* upward in front of the plate *r* to and beyond the lower edge of the inlet *m*. Above the outlet *o* the casing is formed so that its direction of extension is sharply downward, while below the outlet *o*, the casing slopes rearward; thereby directing any stones, striking above or below the outlet, 100 toward the wall *s*.

The material to be treated is fed continuously into the inlet *m* and passes down the chute *t* beneath the deflector *r*, the gate *v* at this time being closed. As the material 105 passes beyond the deflector into the space within the casing it is engaged by the ends

of the rapidly revolving brush blades of the cutters *i*, which tend to cut the rock and release the fibrous asbestos. The material is carried around in the pockets formed between adjacent cutters and is thrown by centrifugal force into the space inclosed by the casing and into engagement with the rapidly revolving cutters *h*, which also perform the cutting or carding action above described. As the material drops by gravity it is again engaged by the revolving cutters and again thrown out into the surrounding space. This action is repeated until most of the fiber is released and by virtue of its finely divided condition it floats to the top and is carried out the outlet *o*. To induce the exhaust of the fiber, holes *w* are provided in the casing, thereby creating a suction of air through the holes into the casing and out of the outlet *o*.

The rapidly revolving knives of the cutters not only separate the fiber from the rock, but they actually elongate the fibers to such an extent that a comparison of the separated product with the original material would apparently indicate that one could not be extracted from the other.

As long as the stones contain any substantial amount of the fiber, they will be caught, as they slide down the rear wall *s*, by the cutters *i* and again subjected to the shredding action described; but when the fiber is substantially removed they slide down the rear wall and rest upon the gate *v*. After the machine has operated for a half hour or so, the gate *v* is opened and the separated rock, stone and dirt allowed to drop through the outlet *n*.

It has been found that if the knives of the cutters are made of uniform length, the separated fiber will not adhere to the cutters sufficiently long to effect any considerable stretching thereof, whereas by gradually decreasing the lengths of the cutters from front to rear of the cutter, the separated fiber will pile up and elongate before it is blown from the cutter. The thicker the cutters from front to rear, the more effective is found to be the stretching action, within reasonable limits. It is found, however, that the lower cutters must be made comparatively thin and the spaces between them comparatively wide in order to take care of the relatively large proportion of grit and heavy material; whereas the material handled by the upper cutters contains a relatively small proportion of grit and stone, thereby permitting the cutters to be made of greater width with smaller spaces between them.

It is found to be necessary to place the lower cutters so that their peripheries pass quite close to the inshoot. Otherwise there would be so thick a mass of material to cut that the machine would clog and a large

proportion of the material fall down to the bottom of the casing. The lower cutters are, however, placed a greater distance from the rear wall in order to permit the material from which the fiber has been separated to pass along the rear wall to the bottom of the casing. The distance between the lower cutters and the rear wall is not, however, so great as to prevent the cutters from contacting with strands of unseparated fiber that may be adhering to and floating out from the stones, thereby drawing such fibers, and the stones attached thereto, around with them and subjecting them to the shredding and stretching action before described.

It is advisable to run the material through the machine more than once, in order that a practically complete separation may be effected.

Having now fully described my invention, what I claim and desire to protect by Letters Patent is:

1. In a machine for separating asbestos, the combination with a casing, of a drum within the casing, means to rotate the drum, and a series of cutters on said drum, each cutter being composed of a multitude of knives of different lengths, the longer knives being nearer the front longitudinal face of a cutter and the shorter knives being nearer its rear longitudinal face.

2. In a machine for separating asbestos, the combination with a casing, of two drums, one above the other, within the casing, means to rotate the drums, and cutters arranged in longitudinal rows on each drum, the thickness from front to rear of the longitudinal cutters on the upper drum exceeding the thickness similarly measured of the longitudinal cutters on the lower drum, there being an inlet in the casing adjacent to the lower drum.

3. In a machine for separating asbestos, the combination with a casing, of two drums, one above the other, within the casing, means to rotate the drums, and cutters arranged in longitudinal rows on each drum, spaced apart to form pockets, the width of the pockets between adjacent longitudinally extending cutters being greater on the lower drum than the width of the similarly formed pockets on the upper drum, there being an inlet in the casing adjacent to the lower drum.

4. In a machine for separating asbestos, the combination with a closed casing, of a plurality of rotary cutter drums in the casing one above the other; said casing being provided with an inlet for the material to be treated below the axis of the lower drum, an outlet for the separated fiber above the axis of the upper drum, and an outlet for the residue at the bottom of the casing.

5. In a machine for separating asbestos, the combination with a closed casing having

front and rear walls converging downwardly, a plurality of rotary cutter drums, one above the other, within the casing; said casing being provided with an inlet for the 5 material to be treated in the lower part of the front of the casing, an outlet for the separated fiber in the upper part of the rear of the casing, and holes creating a suction of air through the casing between said holes 10 and the outlet; and a gate in the bottom of the casing adapted to be opened to permit the discharge of the residue from the bottom of the casing.

6. In a machine for separating asbestos, 15 the combination with a casing having a curved upper portion, a downwardly and inwardly inclined front plate, terminating above the bottom of the casing, a downwardly and inwardly inclined rear wall, terminating at an outlet in the bottom of the 20 casing an inwardly sloping chute extending from outside and above the lower end of the front plate to the lower part of the casing, a rotary drum in the lower part of 25 the casing, cutters thereon rotating in close proximity to the inlet beneath said front plate, a second rotary drum in the upper part of the casing, cutters on the second drum, said casing having in the rear of the 30 curved upper portion thereof an outlet, said outlet being above the level of the axis of the upper drum.

7. In a machine for separating asbestos, 35 the combination with a casing having an arch-shaped upper portion and front and rear walls converging toward a bottom outlet for the rock and stone, of a rotary cutter-carrying drum arranged closer to the front

wall of the casing than to the rear thereof, a second rotary cutter-carrying drum arranged above but relatively close to the lower drum, an inlet in proximity to the lower drum, and an outlet for the separated fiber in the upper portion of the casing. 40

8. In a machine for separating asbestos, 45 the combination with a casing having an arch-shaped upper portion provided with an outlet for the separated asbestos in one wall thereof, and front and rear walls forming the lower portion of the casing and converging toward a bottom outlet for the rock and stone, the front wall having an inlet for the material to be separated, of a rotary drum arranged in the lower portion of the 50 casing, cutters thereon arranged in longitudinal rows spaced apart to form longitudinal pockets, each cutter consisting of a multitude of blades of different lengths the longer blades being nearer the front face of the cutter and the shorter blades nearer the 55 rear face thereof, a rotary drum arranged above and relatively close to the lower drum but relatively far from the top of the casing, cutters on the upper drum constructed and arranged similarly to the cutters of the 60 lower drum but of greater thickness between their front and rear faces, and means to 65 rotate the drums.

In testimony of which invention, I have hereunto set my hand, at Philadelphia, on 70 this 1st day of July, 1911.

JESSE E. WERNER.
